CLAIM

An ornamental design for a display screen with graphical user interface for mobile camera history having collapsible video events, as shown and described.

DESCRIPTION

This application is related to the following applications, all of which are hereby incorporated by reference in its entirety. U.S. patent application Ser. No. 29/530,440, titled “User Interface for Mobile Camera History Having Event-Specific Activity Notifications,” filed Jun. 16, 2015;

U.S. patent application Ser. No. 29/530,442, titled “User Interface for Monitoring and Controlling Remote Video Camera,” filed Jun. 16, 2015;

U.S. patent application Ser. No. 14/738,928, titled “Methods and Systems for Smart Home Automation Using a Multi-function Status and Entry Point Icon,” filed Jun. 14, 2015; U.S. patent application Ser. No. 14/739,412, titled “Methods and Systems for Presenting Alert Event Indicators,” filed Jun. 15, 2015; and

U.S. patent application Ser. No. 14/739,427, titled “Methods and Systems for Presenting a Camera History,” filed Jun. 15, 2015.

FIG. 1 is a front view of a display screen with graphical user interface for mobile camera history having collapsible video events, showing our new design; and,

FIG. 2 is a front view of another embodiment thereof. The broken line showing of a display screen and elements of a graphical user interface is included for the purpose of illustrating portions of the article and forms no part of the claimed design.
